SHOE LASTING DEVICE

Philip Aronov and Walter H. Scott, Chicago, Ill.,
assignors to A. & S. Shoe Engineering Co., Inc.,
Chicago, Ill., a corporation of Illinois

Application January 27, 1937, Serial No. 122,624

23 Claims.

(Cl. 12—7)

The invention relates generally to shoe machinery and more particularly to shoe lasting apparatus.

The primary object of the invention is to provide a novel shoe lasting device which is efficient and reliable in operation and which is capable of producing a well shaped and uniform product.

Another object is to provide a novel shoe lasting device for shaping the entire periphery of the upper in a single operation comprising a plurality of separate steps in each of which a different portion of the upper is drawn tightly against the last, and in each of which as much pressure may be exerted on the portion being shaped as is desired.

Another object is to provide an improved shoe lasting device embodying novel means for drawing the instep portion of the shoe upper tightly against the last to properly shape said portion.

Still another object is to provide an improved shoe lasting device adapted to draw the entire periphery of the upper tightly against the last and embodying novel means for locking the parts in place to maintain the upper in proper shape until permanently set.

A further object is to provide an improved machine for applying the lasting device to the shoe in a convenient and efficient manner constructed so that the lasting device may be operated to shape the different portions of the shoe separately and to apply such pressures to the respective portions as may be needed.

Other objects and advantages will become apparent from the following description taken in connection with the accompanying drawings, in which:

Fig. 1 is a side elevation of a machine and lasting device embodying the features of the invention.

Fig. 2 is a fragmentary plan view of the machine with the last supporting post shown in section.

Fig. 3 is a view, partly in section, showing a detail of the slide mechanism.

Fig. 4 is a plan view of the improved lasting device.

Fig. 5 is a side elevation of the device.

Fig. 6 shows the device as viewed from the under side.

Figs. 7 and 8 are sectional views taken, respectively, along the lines 7—7 and 8—8 of Fig. 4.

Figs. 9 and 10 are sectional views taken, respectively, along the lines 9—9 and 10—10 of Fig. 6.

While the invention is susceptible of various

modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

In the manufacture of shoes, the uppers are ordinarily built up of one or more relatively flat pieces of material sewed or otherwise secured together in the general form of a foot. An upper 11 of this character is shown in Figs. 1 and 5. A welt 12 of the usual form is secured to the upper to provide for attachment of the sole. Before the sole is attached, the upper is shaped by stretching it over a last 13 formed to correspond to the interior of the shoe. In this operation, which is commonly referred to as the "lasting" operation, the flat portion of the upper adjacent the welt is drawn in so as to fit tightly over the rounded edges of the last. Leather uppers are usually shaped while moist and are preferably held in this shaped condition until dry so that the shape will be permanently retained.

The present invention provides an efficient lasting device of unitary construction for drawing in the upper in the above manner in a single operation and for maintaining it in this condition until permanently set. The device is so constructed that different portions of the upper may be drawn in successively to stretch the material evenly and uniformly without weakening it or forming wrinkles therein, thus producing a more durable and better shaped shoe. Novel locking means embodied in the device serves to hold it securely in place upon the shoe to maintain the shoe in proper shape through subsequent operations of the manufacturing process.

Referring more particularly to Figs. 4, 5 and 6 of the drawings, the improved lasting device comprises a frame 14 on which are mounted a flexible member 15 adapted to be drawn tightly around one end of a shoe, and a member 16 adapted to fit around the other end of the shoe and to be sprung into engagement with the sides of the shoe. As herein shown, the frame 14 consists of a generally rectangular plate of sheet metal having the central portion cut away to one edge to form an elongated slot 17 adapted to receive the end of the shoe. The side edges of the plate are bent reversely as at 18 to form 55

parallel grooves 19 (Fig. 10) constituting a guideway for slidably supporting the member 16.

As will be seen by reference to Fig. 6, the member 16 is of generally U-shaped form, the interior edge thereof corresponding closely to the outline of the heel end of a shoe. The end sections 20 of the member are relatively wide and are adapted to fit loosely in the grooves 19 so as to permit limited lateral movement of the member. A tab 21 pressed out at the edge of one of the sections 20 is arranged to cooperate with a notch 22 formed in the side portion 18 of the frame as shown in Fig. 9 to prevent the member 16 from being withdrawn entirely from the guideway.

The end sections 20 of the member 16 are connected by an arcuate strip 23 which is relatively narrow thus providing a degree of flexibility which permits the end sections to be forced inwardly to shape the instep portion of the shoe. By forming the member of thin, flexible sheet material such as spring steel or the like, the end sections 20 may be forced inwardly repeatedly without danger of permanently deforming the strip 23.

Extending rearwardly from the central portion of the connecting strip 21 is a lug 24 which is pivotally connected at 25 to a plate or slide 26 which is slidably supported in the grooves 19 adjacent the rear end of the frame. The slide 26 and member 16 thus move together longitudinally of the shoe, but by reason of the pivoted connection, the member is enabled to shift laterally to accommodate itself accurately to the position of the shoe.

The slide 26 serves to guide the rear end of the member in its movement into operative engagement with a shoe and, in addition, operates to confine such movement within predetermined limits. To this end, the slide is formed with a pair of angularly disposed depending arms 27 (Figs. 6 and 10) which carry headed pins 28 between which a flexible strap 29 is suspended. The strap 29 on engaging the end of the shoe prevents further movement of the member relative to the shoe.

Means is provided for yieldably connecting the member 16 with the frame 14 for movement together as a unit until the member is forced against the end of the shoe with sufficient pressure to properly shape the same and for thereafter permitting relative movement of the member and frame whereby the ends of the member are forced or sprung inwardly to shape the instep portion of the shoe. To this end, rollers 30 carried on each of the end sections 20 of the member are arranged to cooperate with inwardly inclined cam surfaces 31 formed on the ends of the inturned side portions 18 of the frame. The positioning of the rollers is such that, in the movement of the cam surfaces thereover, the end sections of the member are pressed inwardly. Such movement is resisted by the spring action of the strip 23 which tends to hold the end sections spread apart so that the member is carried forward with the frame until its movement is arrested by the strap 29 engaging the heel of the shoe. Upon further movement of the frame, the cam surfaces slide over the rollers and press the end section 20 inwardly thus drawing the instep portion of the upper over the last.

The remaining portion of the upper forward of the instep is drawn over the last by the flexible member 15. In its preferred form, the member 15 comprises a wire of spring steel or the like

which may be repeatedly drawn into the shape of the shoe without becoming permanently bent. This wire is arranged in the form of a loop adapted to be placed around the toe portion of the shoe, preferably in the groove formed by the seam joining the upper and the welt as shown in Fig. 5.

The wire 15 is assembled with the other elements of the lasting device by carrying the ends rearwardly through suitable guide slots 32 formed in the respective end sections 20 of the member 16, apertures 33 in the arms 27 of the plate 26 and thence through apertures 34 in a depending flange 35 formed along the rear edge of the frame 14. The projecting ends are anchored to rigid bar 36 which serves as an actuator for drawing the wire through the frame to tighten it around the toe of the shoe. When the shaping member 16 is sprung inwardly, the wire 15 is forced against the sides of the shoe by the action of the end sections 20 in which the wire guide slots are located. This also serves to draw the wire tighter against the end of the shoe.

In the preferred form of the device, means is provided for holding the wire against forward movement after being drawn around the shoe so as to lock the parts of the lasting device in place while other operations are performed in the shoe or until the shoe becomes permanently set in the desired shape. It will be appreciated, of course, that the locking means may be dispensed with if desired, particularly when the sole is attached to the upper immediately after the shaping operation. In this case, the upper is held in shape by the sole until it becomes permanently set.

As herein shown, the locking means for the lasting device comprises an elongated flat metal strip 37 rigidly secured to the bar 36 intermediate its ends and arranged to project substantially below the lower edge of the bar. The strip is formed with an aperture adapted to receive a horizontally disposed cylindrical rod 38 which is bolted or otherwise rigidly secured to the flange 35 of the frame 14 so as to project rearwardly of the frame. The aperture in the strip is of sufficient size to permit the strip to move freely relative to the bar when the strip is perpendicular to the rod. When the strip is tilted, however, the edges of the aperture bind on the rod and prevent relative movement between the parts. Such tilting is produced by the tension of the wire 15 when drawn tightly around the shoe. Thus forward movement of the wire is effectually prevented and the wire is held tightly in place around the shoe.

In order to prevent the strip 37 from tilting when the wire is being drawn rearwardly, the upper end of the strip is bent over and down in back of the bar 36 to form a stop 39 adapted to abut against the rod 38 and hold the strip 37 in an upright position. The stop slides freely over the rod in the rearward movement of the actuator 60 and does not interfere in any way with the tilting of the strip when the actuating force is withdrawn from the bar 36.

A machine particularly adapted for applying the lasting device to a shoe is illustrated in Fig. 1. While the parts of the machine may be supported in any suitable manner, we have shown them as mounted on a table or bench having a flat, horizontal top 40 and legs 41 adapted to rest upon the floor 42.

As herein shown (Figs. 1 to 3), the machine includes a slide 44 supported for movement transversely of the table in a guideway formed by spaced parallel side members 45 bolted or otherwise rigidly secured to the table top 40. The slide

44 is normally held in a forward position with one end projecting substantially beyond the front edge of the table top by a coiled compression spring 46 acting on the inner end of the slide. 5 For this purpose one end of the spring is seated in a socket 47 in the end of the slide and the other end bears against a sleeve 48 mounted in a cross member 49 which connects the two side members 45 at their inner ends. A rod 50 anchored to the slide passes through the coiled spring 46 and sleeve 48 and, through the medium of a nut 51 threaded on the projecting end, operates to limit the forward movement of the slide.

Centered over the slide and supported by the 15 side members 45 is a vertically projecting last supporting post 52 (Figs. 1 and 2). The post is preferably bored out to slidably receive a rod 53 which carries the last 13 on its upper end. By 20 sliding the rod into or out of the post, the last may be adjusted to the desired position relative to the other parts of the machine. A set screw 54 threading into the post is provided for locking the rod in set position.

Pivoted intermediate its ends upon the projecting end of the slide 44 is a lever 55 arranged to operate the lasting device. To this end, the lever is formed with spaced parallel side members 56 which are spread apart at their upper ends so as to straddle the guide rod 38 of the lasting device 30 when the lever is inserted between the actuator 36 and the rear edge of the frame 14. A spacer 57 on the rod 38 normally holds the actuator spaced substantially from the frame to permit entry of the end portions 56 of the lever therebetween, the portions being suitably tapered as at 58 to facilitate such entry.

For swinging the lever 55 about its pivot, a flexible member such as a chain 59 is attached to its lower end and, after passing over a pulley 60 fixed to the underside of the table top, is secured to a lever 61. The lever 61 is pivotally supported at its inner end by a bracket 62 anchored to the floor and its outer end, which projects beyond the table, is enlarged to form a foot pedal 62a for actuating the lever. A coiled tension spring 63 connecting between the lever 61 and the underside of the table top tends to hold the pedal in a raised position. A similar spring 61a acting on the upper end of the lever 55 tends to hold it in the forward position shown and to maintain the chain 59 taut. When the pedal is depressed, the lever 55 is rocked about its pivot to move the actuator rearwardly and thus draw the wire 15 tightly around the shoe mounted on the last 13. 55 In this operation, the slide 44 is held in its normal position by the action of the spring 46.

When the wire 15 has been drawn sufficiently tight around the shoe to give it the desired shape, the spring 46 yields and permits the slide to move rearwardly so that the upper end of the lever remains substantially stationary and holds the wire in tightly drawn condition upon further depression of the pedal. This movement of the slide 44 is utilized to move the frame 14 of the lasting device longitudinally of the shoe thereby moving the shaping member 16 into operative engagement with the shoe. To this end the slide carries a vertically projecting arm 64 tapered at its upper end as at 64a for insertion between the actuator 36 and the flange 35 of the lasting device. The end of the arm is bifurcated as at 65a (Fig. 4) to accommodate the rod 38 and the spacer 57. Upon forward movement the arm is adapted to abut against the flange 35 of the frame, thus carrying the frame forwardly toward the last 13.

As explained above, the forward movement of the frame first moves the U-shaped member 16 into tight engagement with the heel end of the shoe and subsequently presses the end portions of the member inwardly to shape the instep portion of the shoe. Thus the entire shoe is shaped in three separate and distinct steps effected successively by the depression of the pedal 62. 5

When the foot pedal is released, the slide 44 and lever 55 are returned to normal position by 10 the action of the springs 46 and 63, respectively. Movement of either part beyond the normal position is prevented by a stop in the form of a pin 65 carried on the arm 64 and adapted for engagement by the lever 55. The shaping elements 15 of the lasting device are not returned to normal position at this time, however, being locked in place as hereinbefore described. The last with the upper in place thereon may thus be removed from the machine for further operations. 20

It may be desirable, at times, to increase the pressure of the wire 15 on the toe end of the shoe over that applied in the operation above described. To this end means is provided to lock the slide 44 against movement so that any desired pressure may be applied to shape the toe end of the shoe before the other shaping elements are operated. As herein shown, the locking means comprises a lever 66 (Fig. 2) pivotally supported at one end in a slot 67 formed in one of the side 30 members 45. The lever is formed with a cam surface 68 adapted to engage the side of the slide and thus lock it against movement when the lever is rocked on its pivot.

In order to hold the upper 11 tightly on the last 35 during the shaping operation, means is provided for clamping it securely to the last. The clamping means comprises, in the present instance, an arm 69 pivotally supported at one end on a horizontal shaft 70 journaled in stationary brackets 40 71 mounted on the side members 45. The other end of the arm is formed with a rounded head 72 adapted to press against the instep portion of the shoe when the member is rocked to the position shown in Fig. 1. This rocking action may be 45 effected by any convenient means such as a hand lever 73 fast on the shaft 70.

It will be apparent from the foregoing that the invention provides a novel and useful lasting device capable of forming the entire periphery of 50 the shoe in a single operation. The device is arranged to lock automatically when applied to the shoe so that the shoe is held in desired shape until permanently set or while other operations are performed thereon. Moreover, the 55 device may be used repeatedly.

We claim as our invention:

1. A shoe lasting device comprising, in combination, a member adapted to be drawn tightly around one end of a shoe, and a plate of spring 60 material movable in a direction opposite to said member and adapted to fit around the other end of the shoe parallel to the sole and means operable upon engagement of said plate with the end of the shoe to spring the plate edgewise into engagement with the sides of the shoe. 65

2. A shoe lasting device comprising, in combination, a member adapted to be drawn tightly around one end of a shoe, and a U-shaped plate of spring material adapted to fit 70 around the other end of the shoe and to be forced against the sides of the shoe, said plate having its ends engaging said member to likewise force said member against the sides of the shoe.

3. A shoe lasting device comprising, in combi- 75

- nation, a flexible member adapted to fit around one end of a shoe, a U-shaped member adapted to fit around the other end of the shoe, slots in said U-shaped member for positioning and guiding said flexible member adjacent the sides of the shoe, means for moving said members relative to each other longitudinally of the shoe to shape the ends thereof, and means for moving the slotted portions of said U-shaped member laterally to force the ends of such member and said flexible member against the sides of the shoe to shape the same.
4. A shoe lasting device comprising, in combination, a flexible member adapted to fit around one end of a shoe, a U-shaped member adapted to fit around the other end of the shoe, means attached to said flexible member adapted to be drawn longitudinally of the shoe to tighten the flexible member around one end of the shoe,
- 20 a frame supporting said U-shaped member, means for moving said frame longitudinally of the shoe, and coacting means on said frame and said U-shaped member tending to cause the frame and member to first move simultaneously to carry the member into operative engagement with the other end of the shoe to shape the same and then to force the ends of the member inwardly to shape the sides of the shoe.
5. A shoe lasting device comprising, in combination, a rigid frame adapted to extend partially around a shoe, a wire supported on said frame to define a loop adapted to fit around one end of the shoe, a U-shaped plate adapted to fit around the other end of the shoe, and means for supporting said plate on said frame comprising a slide mounted for reciprocation in said frame, said plate being pivotally connected to said slide to permit the plate to adjust its position automatically with respect to the shoe.
- 40 6. A shoe lasting device comprising, in combination, a member adapted to fit around one end of a shoe, and a U-shaped plate adapted to fit around the other end of the shoe, said U-shaped plate being pivotally supported to enable it to accommodate itself to the position of the shoe.
7. A shoe lasting device comprising, in combination, a wire adapted to be drawn tightly around one end of a shoe, a frame for supporting and guiding said wire, an actuator including a transverse member secured to the respective ends of the wire at the rear of said frame, and means on said frame coacting with said actuator to guide the same when drawn rearwardly to tighten said wire and to frictionally engage the same to hold the wire tight.
- 60 8. A shoe lasting device comprising, in combination, a wire adapted to be drawn tightly around one end of a shoe, a frame for supporting and guiding said wire, a rod projecting rearwardly from said frame, an actuator including a pair of crossed bars one of which is secured to the respective ends of said wire at the rear of said frame, the other of said bars having an aperture adapted to slidably receive said rod, said rod cooperating with said other bar to guide the actuator for rearward movement to tighten said wire and to frictionally resist forward movement of the actuator to loosen the wire.
- 65 9. A shoe lasting device comprising, in combination, a flexible member adapted to be drawn tightly around one end of a shoe to shape the same, a U-shaped plate member adapted to be pressed around the other end of the shoe to shape the same, a frame for supporting said U-shaped plate member, and means secured to said

flexible member cooperating with means on said frame to hold said members tightly against the shoe and to lock them in place.

10. A shoe lasting device comprising in combination, a flexible member adapted to be drawn tightly around one end of a shoe to shape the same, a rigid member adapted to fit around the other end of the shoe, a U-shaped member mounted on said rigid member adapted to be pressed tightly against said other end of the shoe to shape the same, and means secured to said flexible member cooperating with means on said frame to hold the flexible member and said U-shaped member tightly against the shoe and to lock them in place.

15 11. A shoe lasting device comprising, in combination, a rigid frame adapted to fit around one end of a shoe, said frame having spaced guideways extending along opposite sides of the shoe, a U-shaped member supported in said guideways for movement relative to said frame, and means connecting said members and said frame for movement together to carry the member into operative engagement with the shoe, said connecting means yielding upon engagement 25 of the member with the shoe to permit continued movement of said frame while the member remains stationary.

12. A shoe lasting device comprising, in combination, a rigid frame adapted to fit around one end of a shoe, said frame having spaced guideways extending along opposite sides of the shoe, a U-shaped member supported in said guideways for movement relative to said frame, means yieldably connecting said member and 35 said frame to cause the parts to move together until the member operatively engages the end of the shoe and to permit continued movement of said frame while the member remains stationary, and means operative in such continued 40 movement of said frame for forcing the ends of said member inwardly against the sides of the shoe.

13. A shoe lasting device comprising, in combination, a rigid frame adapted to fit around one end of a shoe, said frame having spaced guideways extending along opposite sides of the shoe, a plate slidably supported in said guideways, a U-shaped member supported in said guideways and connected to said plate for movement therewith, means yieldably connecting said member and said frame for movement together to carry the member into engagement with the shoe, and stop means on said plate engageable with the shoe for limiting the extent of movement of said 55 member relative to the shoe.

14. A shoe lasting device comprising in combination, a rigid frame adapted to fit around one end of a shoe, said frame having spaced guideways extending along opposite sides of the shoe, a plate slidably supported in said guideways, a U-shaped member loosely supported in said guideways for limited movement laterally of said frame and pivotally connected to said plate for movement therewith longitudinally of the 65 frame, and means yieldably connecting said member and said frame to cause all of said parts to move together to carry the member into operative engagement with the shoe for shaping the same.

70 15. A shoe lasting device comprising, in combination, a rigid frame adapted to fit around one end of a shoe, said frame having spaced guideways extending along opposite sides of the shoe, a U-shaped member supported in said guide- 75

ways for movement relative to said frame, and means yieldably connecting the member and the frame for movement together comprising cam surfaces formed on said frame adjacent the ends of said guideways adapted to engage followers mounted on the ends of said member.

16. A shoe lasting device comprising, in combination, a rigid frame adapted to fit around one end of a shoe, said frame having spaced guideways extending along opposite sides of the shoe, a U-shaped member supported in said guideways for movement relative to said frame, means yieldably connecting the member and frame for movement together in one direction, and means for preventing relative movement between the member and the frame in the other direction.

17. A machine for lasting shoes comprising, in combination, a work support for a last adapted to receive the shoe, a wire looped around one end of the shoe with the ends extending rearwardly of said last, a transversely disposed bar connected to the ends of said wire, a U-shaped plate adapted to fit around the other end of the shoe, a frame supporting said plate, a lever adapted to engage said bar to draw the same rearwardly and tighten said wire around the shoe, a slide pivotally supporting said lever and having an arm engageable with said frame to force the frame and said plate forwardly against the shoe, a pedal for swinging said lever, and a spring acting on said slide to maintain it in normal position during the initial movement of said lever by said pedal to tighten said wire around the shoe, said spring permitting forward movement of the slide to force said plate against the shoe upon further movement of the pedal and lever after the wire has been drawn tightly around the shoe.

18. A machine for lasting shoes comprising, in combination, a work support for a last adapted to receive the shoe, a wire looped around one end of the shoe with the ends extending rearwardly of said last, a transversely disposed bar connected to the ends of said wire, a U-shaped plate adapted to fit around the other end of the shoe, a frame supporting said plate, a lever adapted to engage said bar to draw the same rearwardly and tighten said wire around the shoe, a slide pivotally supporting said lever and having an arm engageable with said frame to force the frame and said plate forwardly against the shoe, a spring resisting forward movement of said slide, a pedal normally operative when depressed to first swing said lever to tighten said wire around the shoe and then to force said slide forwardly against the action of said spring to move said plate into engagement with the shoe, and locking means operable to prevent forward movement of said slide.

19. A machine for setting a shoe lasting device including a pair of members adapted to be moved

into clamping engagement with the respective ends of a shoe, said machine comprising, in combination, a fixed support for the shoe, a pair of elements for forcing one of said members in one direction against the shoe and for drawing the other member in the opposite direction against the shoe, common means for operating said elements, and means for locking one of said elements against movement to permit the other element to complete its movement.

20. A machine for setting a shoe lasting device including a pair of members adapted to be moved into clamping engagement with the respective ends of a shoe, said machine comprising, in combination, a fixed support for the shoe, a slide for forcing one of said members into engagement with the shoe, a lever pivotally supported by said slide for drawing the other member into engagement with the shoe, common means for swinging said lever and for moving said slide, and locking means for holding said slide against movement whereby said common means serves to operate said lever alone.

21. A machine for lasting shoes comprising, in combination, a work support for a last adapted to receive a shoe, a flexible member adapted to fit around one end of the shoe, a U-shaped plate adapted to fit around the other end of the shoe, actuating means including a pedal for performing the operation of drawing said member tightly around the shoe and of forcing said plate into engagement with the shoe, and clamping means operable to confine said actuating means to performance of only one of said operations.

22. A shoe lasting device comprising, in combination, a wire adapted to be drawn tightly around the toe of a shoe, a U-shaped plate adapted to fit around the heel of the shoe and forwardly to the wide portion of the shoe, a frame member, said plate being supported by said frame member to permit a forward movement of the plate into position on the shoe to cause it to fit snugly at the rear of the heel and at that part where the shoe converges from its wide portion to the instep, the forward portion of said plate at the same time having a laterally inward movement to fit tightly on the sides of the shoe.

23. A shoe lasting device comprising, in combination, a wire adapted to be drawn tightly around the toe of a shoe by a rearward movement, a U-shaped plate shaped to fit around the heel of the shoe and arranged to be moved forwardly into position on the shoe, and means on said plate for drawing the wire vertically into conformity with the contour of the shoe as the wire is drawn rearwardly and the plate is moved forwardly.
